UNITED STATES PATENT OFFICE.

ALPHA B. CULP, OF WAKARUSA, INDIANA.

MOWING APPARATUS.

1,121,984.

Specification of Letters Patent.

Patented Dec. 22, 1914.

Application filed August 5, 1913. Serial No. 783,081.

To all whom it may concern:

Be it known that I, ALPHA B. CULP, a citizen of the United States, residing at Wakarusa, in the county of Elkhart and 5 State of Indiana, have invented certain new and useful Improvements in Mowing Apparatus, of which the following is a specification.

My invention relates to an improvement 10 in hay mowing apparatus, and the object is to provide tracks radiating from a common point for delivering the hay to different portions of the barn, and further, in the provision of a switch at the common radiating point of the tracks so that the carrier can be caused to travel upon any track desired by merely throwing the switch to a position so that the carrier can run on to the desired track.

20 The invention consists in certain novel features of construction and combinations of parts which will be hereinafter described and pointed out in the claims.

In the accompanying drawings: Figure 1 25 is a bottom plan view of the track and switch showing the same mounted to the rafters of a barn. Fig. 2 is a perspective view of the switch; Fig. 3 is a perspective view looking toward one side of the switch; 30 Fig. 4 is an end view; Fig. 5 is a bottom plan view of the switch.

A represents the rafters of a barn to which the tracks B are connected, and which all radiate from the center of the barn, and 35 located between the inner ends of the tracks is a switch C. Mounted upon the joists 1, 1 are two parallel bars 2, 2. Connecting these bars at the center is a cross bar 3. Pivotally mounted upon the cross bar and located 40 between the parallel bars 2 is a switch C, which consists of a block member. Carried by the block member C is a track 4, which is fastened to the member C by means of bolts 6 and nuts 7. A shifting block 8 is 45 connected at one end to the member C by means of plates 9. Pivotally connected to the block 8 are latches 10. These latches are adapted to engage the bars 2; when one of the latches is in engagement with the bar 2, 50 it locks the member C against the bar and causes the track to have registry with one of the tracks B. Only one latch is in engagement with a bar 2 at the same time. Connected to each of the latches 10 are ropes 55 11 and 12.

Mounted upon the block 8 are pulleys 13,

13. The rope 11 passes over the pulley 13 and thence over a pulley 15 carried in the bracket 16 mounted upon the joist 1, and thence over a pulley 17 carried on a track 60 18, which is mounted upon the joist 1. The other rope 12 passes over the pulley 14 and is carried over a pulley 19 mounted on the bracket 18. These ropes 11 and 12 extend down to the floor of the barn where they 65 can be grasped for the purpose of shifting the switch to bring the track 4 into registry with one of the tracks B.

Pivots mounted upon each of the rafters 1 are guard plates 20. These guard plates extend downwardly over the hangers 21 which support the tracks B to the rafters and prevent the carrier (not shown) from passing on to the tracks until the switch has been moved the required distance. A 75 stud or pin 22 is mounted in the ends of the block member C and when the pin is brought into engagement with one of the guard plates 20, the guard plate will be oscillated so that the carrier can travel onto the track 80 with which the switch track 4 has been into registry. Without these guard plates 20 the carrier might be thrown off from the switch track 4 before the switch member C has been thrown the proper distance prior to the engagement of the bar 2 by the latch 10.

From the disclosure made in Fig. 1, it will be noted that the switch is locked at the center of the barn preferably, and that the oscillation of the switch permits of the carrier being conducted to either end of the bar.

Ropes 23 and 24 are connected to opposite ends of the carrier and pass about pulleys at each end of the barn, and then are conducted to the center of the barn, where they 95 are accessible to the operator so that the car can be drawn with its load to either end of the barn.

The object of this device is to remove the hay, wheat, or grain from the vehicle in 100 sling loads and with an arrangement of this character, the hay could be mowed away by one or two persons.

Having fully described my invention, what I claim as new and desire to secure by 105 Letters Patent is:

1. In a mowing apparatus, the combination with tracks, of a switch located in proximity to and adapted to register with said tracks, latches for locking the switch in its 110 shifted position, only one of the latches being in engagement at a time, and means for

operating the switch for causing it to be shifted into registry with the desired track, said means connected to the latches, whereby only the latch which is holding the switch

5 against movement is actuated for releasing the switch upon the shifting of the switch.

2. In a mowing apparatus, the combination with tracks, of a switch located in proximity to and adapted to register with said

10 tracks, latches for locking the switch in its shifted position, and means independently connected to each of the latches for operating the latches independently of each other, only one of the latches adapted to be in en-

gagement at a time for holding the switch 20 against movement, said means adapted to operate said last-mentioned latch for releasing the switch and for causing the switch to be shifted, the other latch adapted to automatically lock the switch against movement after it has been shifted. 25

In testimony whereof I affix my signature, in the presence of two witnesses.

ALPHA B. CULP.
